UNITED STATES PATENT OFFICE.

MARY HENRIETTA V. OTWELL, OF CARLINVILLE, ILLINOIS.

SANITARY HANDKERCHIEF-CONTAINER.

1,344,927.

Specification of Letters Patent. Patented June 29, 1920.

Application filed June 9, 1919. Serial No. 302,760.

To all whom it may concern:

Be it known that I, MARY HENRIETTA V. OTWELL, a citizen of the United States, residing at Carlinville, in the county of Ma-
5 coupin and State of Illinois, have invented certain new and useful Improvements in Sanitary Handkerchief-Containers, of which the following is a specification.

This invention relates to special recep-
10 tacles and more particularly a handkerchief receptacle.

The primary object of this invention re-
sides in the provision of a receptacle whereby
15 a multiplicity of handkerchiefs may be re-
tained in separate compartments before
and after use.

A further object of this invention resides
in the provision of a receptacle whereby a
20 plurality of unsold handkerchiefs may be re-
tained in a sanitary condition in a com-
partment from which they may be readily
removed as desired.

A further object of this invention resides
in the provision of a receptacle, the various
25 elements of which coact in retaining the
handkerchiefs within their respective com-
partments until removed by hand.

With these and other objects in view this
invention resides in certain novel features
30 of construction, arrangements and combi-
nation of elements to be hereinafter more
fully set forth and it is to be understood
that certain departures may be resorted to
as come within the scope of the appended
35 claims.

In the accompanying drawing.

Figure 1 is a side view of the receptacle
showing a handkerchief about to be re-
moved.

40 Fig. 2 is an enlarged longitudinally sec-
tional view on line 2—2 of Fig. 1.

Fig. 3 is a sectional view on line 3—3 of
Fig. 1.

45 Fig. 4 is a detail perspective view of the
cylinder for holding the handkerchiefs.

Fig. 5 is a perspective view of a modified
form of the receptacle.

In the present embodiment of this in-
vention, the numeral 5 designates a casing
50 which when utilized for transportation in
the pocket or pocket book of a person may
be ornamentally decorated or covered with
any desired fabric or suitable covering.

55 The aforesaid casing 5 has one end sealed
by an apertured cap 6 which may be formed
integrally therewith should the cylinder be

pressed from a single piece of material or
it may be permanently secured thereto in
any approved manner.

Secured to the cap 6 and extending with-
in said cylinder in spaced relation to its
walls is a cylindrical sleeve 7 to form a
compartment 7' for the reception of soiled
handkerchiefs or the like. This sleeve is
provided with an annular groove 8 upon
its outer periphery adjacent that end which
is secured to said apertured cap for a pur-
pose to be hereinafter set forth.

In order to seal the open end of said
compartment, a cover 9 is provided which
may be secured to the casing in any ap-
proved manner and held in closed position
by any suitable fastening element.

Surrounding the aforesaid sleeve 7 is a
drum 10 having a flange 11 of a sufficient
75 diameter secured to its outer end to extend
to the periphery of the casing 5, in order
that the entrance to the compartment 12
will be sealed when the above elements are
assembled. Adjacent that end of the drum 80
10 that bears against the cap 6 is an annu-
lar bead 13 which is adapted to seat in the
annular depression or groove 8, to hold the
drum in operative position. In order that
the open end of said drum may expand to
85 allow the displacement of the bead, and sub-
sequent removal of the drum, a slit 14 is
cut in the drum.

Wound or otherwise retained upon said
drum is a multiplicity of handkerchiefs 15
90 which are retained in the compartment 12
with a portion of the one next to be with-
drawn therefrom projecting through a slot
16 in the casing, thus it is apparent that
but a single handkerchief can be removed 95
at a time.

In order to retain the handkerchief in a
compact condition and to prevent the acci-
dental unwinding of the same, the drum
is provided with a resilient tongue 17 that 100
frictionally engages the periphery of the
sleeve 7.

As the handkerchiefs employed with this
receptacle are to be manufactured of paper,
they must necessarily be made attractive in 105
design and may also be perfumed.

In the form shown in Fig. 5 the recep-
tacle consists of compartments 18 and 19,
the former of which being utilized for soiled
handkerchiefs and the latter for the unused 110
handkerchiefs. This form of receptacle is
employed for use in hospitals and is of such

size as to need but a minimum amount of attention.

Having thus fully described this invention, it is apparent that a necessity has been provided which enables the introduction of a material in substitution for fabric handkerchiefs which is more sanitary and inexpensive to manufacture.

What I claim is:

10. A non-liquid container comprising a cylindrical member, one end being closed by means of a bottom, the opposite open end being surrounded by means of an outstanding circumscribing flange, a cap closing said container, a tubular casing extending from said

flange and ending in alinement with said cylindrical member, said casing having a longitudinally extending slot, and a drum closed at one end surrounding said cylindrical member and stopped against said flange the other end being closed by means of a plate stopped against said cylindrical member, as and for the purpose set forth. 20

In testimony whereof I affix my signature in the presence of two witnesses.

MARY HENRIETTA V. OTWELL.

Witnesses:

G. W. JOHNSON,
MARY JOHNSTON.
